UNITED STATES PATENT OFFICE.

ANDREW B. CLARK, OF THOMASVILLE, GEORGIA, ASSIGNOR OF ONE-HALF TO ROSCOE LUKE, OF THOMASVILLE, GEORGIA.

DOORCHECK.

Application filed March 14, 1927. Serial No. 175,177.

This invention aims to provide novel means for checking the closing movement of a door, the device being adjustable at the will of an operator.

5 It is within the province of the disclosure to improve generally and to enhance the utility of devices of that type to which the invention appertains.

With the above and other objects in view 10 which will appear as the description proceeds, the invention resides in the combination and arrangement of parts and in the details of construction hereinafter described and claimed, it being understood that changes 15 in the precise embodiment of the invention herein disclosed, may be made within the scope of what is claimed, without departing from the spirit of the invention.

In the drawings:—

20 Figure 1 shows in plan, a device constructed in accordance with the invention; Figure 2 is an elevation; Figure 3 is an elevation looking toward the bracket; Figure 4 is a plan showing a modification; and Figure 5 is a section on the line 5—5 of Figure 4.

The numeral 1 marks a door frame to which a door 2 is hinged at 3, a bracket 4 being secured to the door frame 1, the bracket comprising a base 5 and arms 6 and 7 projecting 30 from the base approximately at right angles thereto, the base 5 having a socket 8 provided with a slot 9 in which moves a screw 10 having a ball 11 which rocks in the socket 8. The screw 10 has a wide portion 12 and a narrow portion 14, between which is located a circumferential groove 15. A spring tongue or brake 16 is attached by securing elements 17 to the arm 7 and is located about parallel to the base 5, the spring tongue 16 having an inclined end 40 18. The spring tongue or brake 16 bears on the wide portion 12 of the screw 10 and is held in adjusted positions by means of a screw 19 threaded into the arm 6.

A nut 20 is threaded on the screw 10, the screw traveling through the nut. The nut 20 has a shaft 21 which is journaled in an angle bracket 22 on the door 2.

When the door moves from open position to closed position, the wide portion 12 of the screw 10 is carried by the end 18 of the spring tongue 16, under the spring tongue, the spring

tongue bearing on the wide portion 12 of the screw 10 and limiting, adjustably, the rotation of the screw 10, the screw 10 being rotated because the nut 20 is threaded on the screw. The 55 construction of the device is such that it will check the closing movement of a door efficiently and adjustably.

In the form shown in Figures 4 and 5, parts hereinbefore described have been designated 60 by numerals previously used with the suffix "a".

A bracket 23 is secured to the door frame 1^a, and to the bracket 23, a holder 24 is pivoted as at 25, the holder 24 being provided with a 65 recess 26 which receives the inner end of a screw 10^a, including the ball 11^a. The holder 24 carries a bearing 27 which is received in the groove 15^a of the screw 10^a, the screw thus being held on the holder 24 for rotation. A 70 spring brake 28 is provided and bears on the widened portion 12^a, of the screw 10^a, the spring brake 28 being secured at one end, as at 29, to the holder 24. The opposite end of the spring brake 29 is engaged by a screw 30 75 threaded into the holder 24. A lock nut 31 on the screw 30 cooperates with the holder 24 to maintain the screw 30 in adjusted position, and the function of the screw 30, of course, is to adjust the pressure with which the spring 80 brake 28 bears on the part 12^a of the screw.

In the form shown in Figure 2, the screw 10 swings in the bracket 4, whereas, in Figure 4, the screw 10^a rotates in the member 24, and the member 24 swings on the bracket 23. 85

What is claimed is:—

1. In a door check, a bracket, means for mounting the bracket on a door frame, a screw, means for mounting the screw for rotation and for swinging movement on the 90 bracket, a nut into which the screw is threaded, means for mounting the nut pivotally on a hinged door, a brake strip cooperating with the screw and extended across the screw in a direction approximately at right angles to 95 the length of the screw, means for securing one end of the brake strip, and mechanism engaging the brake strip, in spaced relation to the last specified means, for adjusting the braking effect of the strip on the screw. 100

2. In a door check, a bracket, means for mounting the bracket, a screw, means for

mounting the screw for rotation and for swinging movement on the bracket, a nut into which the screw is threaded, means for mounting the nut pivotally, a brake strip extended across the screw, and means for securing the brake strip at one end, the brake strip being of such length that the screw can swing en-

tirely clear of the brake strip when the door to which the check is applied moves to an open position.

10

In testimony that I claim the foregoing as my own, I have hereto affixed my signature.

ANDREW B. CLARK.
